UNITED STATES PATENT OFFICE.

WILLARD COMEY, OF WESTBOROUGH, MASS., ASSIGNOR TO THE IMPROVED SOLE SEWING MACHINE COMPANY, OF THE STATE OF MAINE.

BOOT AND SHOE SEWING MACHINE.

SPECIFICATION forming part of Letters Patent No. 250,647, dated December 13, 1881.

Application filed June 27, 1881. (No model.)

To all whom it may concern:

Be it known that I, WILLARD COMEY, a citizen of the United States, residing at Westborough, in the county of Worcester and State of Massachusetts, have invented certain Improvements in Boot and Shoe Sewing Machines, of which the following is a full, clear, and exact description, reference being had to the accompanying drawings, making part of this specification, in which—

Figure 1 is a side elevation of a boot and shoe sewing machine having my improvements applied thereto. Fig. 2 is a front elevation of the same. Fig. 3 is a perspective view of a portion of the front of the machine. Fig. 4 is a horizontal section on the line $x-x$ of Fig. 2; Fig. 5, sectional detail.

My invention has for its object to facilitate the operation of sewing welts to the inner soles 20 of boots and shoes, and at the same time to keep the edge of the welt along its entire length at a uniform distance from the vamp or upper, thus insuring perfect work and avoiding the necessity of close attention on the part 25 of the operator in guiding the welt, as would be required if it was laid by hand.

To this end my invention consists in a sliding bar or pressure device, the lower end of which is brought down into contact with the 30 welt and then moved in such a manner as to press the welt outward from the sole against a guide-roll placed opposite thereto, and provided with two flanges, between which the welt passes, and by means of which it is kept in its 35 proper position, the periphery of the lower flange serving as a gage or rest against which the boot or shoe is pressed by the operator, while that portion of the roll located between the flanges serves as a gage or rest for the 40 edge of the welt, which, by being pressed constantly against it by the sliding bar, is thus kept throughout its entire length at a uniform distance from the vamp resting against the edge of the adjacent flange.

My invention also consists in certain details 45 of construction, as hereinafter set forth and specifically claimed.

In the said drawings, A represents the framework of the machine, which is supported, as

usual, on a column or standard, B, having a 50 suitable base. (Not shown.)

D represents the movable work-supporting horn, which is provided with the usual rotating whirl for laying the waxed thread in the hook of the needle.

The needle *a*, its bar or stock *b*, the cast-off *c*, and its bar or stock *d*, together with the presser-foote and its bar *f*, and their respective operative mechanisms, are all constructed in the usual manner common to machines of this 60 description, and, as they form no part of my present invention, will not be further described.

To the oscillating frame *G*, which carries the needle-bar *b* and cast-off bar *d*, is screwed a vertical spring-bar, *H*, which slides in the direction of its length in guides *g h* on the frame *G*, and is held within the bifurcated guide *h* by means of a screw, 10, passing through a slot, *k*, there being sufficient friction between the guide *h* and the bar to hold the latter in any position in which it may be left. The lower end of this bar *H*, which is bent into the form seen in Figs. 1 and 2 to bring it over the edge of the tip of the horn *D*, is preferably provided with a removable sharp-pointed projection, *i*, adapted to penetrate a short distance into the surface of the welt *I*, Figs. 3 and 5, on the descent of the bar; but the lower end of this bar *H* may be serrated or roughened or otherwise constructed to prevent it from slipping upon the 80 welt when pressed down firmly thereon.

In the operation of sewing the welt to the inner sole, *N*, as the needle-bar *b* is carried down by the connecting-rod *K* attached to the crank *l* an adjustable projection, *m*, on the rod *K* strikes 85 against the free end of a stiff flat spring, *p*, secured to the bar *H*, which is thus carried down, during the latter part of the descent of the needle, until its projection *i* is brought into contact with and penetrates the welt, and as soon 90 as the needle has ascended above the tip of the horn and the presser-foot *e* is raised from off the surface of the work the frame *G* is oscillated with the needle in the usual manner to produce the feed, carrying with it the lower end 95 of the spring-bar *H*, the lateral movement of which causes its beveled edge 15 to travel in contact with the wedge-shaped or inclined face

16 of an adjustable piece, *q*, attached to the stationary block through which the presser-foot bar *f* slides, and thus, as the lower end of the bar *H* is moved laterally by the frame *G*, it is carried inward, against its own tendency to spring outward, by the wedge or inclined face 16 in an oblique direction, which causes it to press the welt *I* outward from the sole *N* and keep its edge 17 constantly in contact with the central portion, 18, of a rotating guide-roll, *M*, which is supported on a stud, *r*, projecting down vertically from a bar or arm, *L*, pivoted to the frame-work at *s* and made adjustable by means of a screw, *t*, passing through a slot, 15 *u*. The guide-roll *M* is provided with two flanges, *v w*, between which the welt passes, and by means of which it is kept down upon the sole *N*, the periphery of the lower flange, *w*, serving as a gage or rest, against which the upper of the shoe is pressed by the operator, and consequently, as the upper is kept against the edge of the flange *w* and the outer edge, 20 17, of the welt is kept constantly against the smaller central portion, 18, of the roll *M*, as seen in Fig. 5, by the oblique pushing movement of the bar *H*, the outer edge of the welt is always maintained at a uniform or unvarying distance from the vamp or upper, as desired, and all liability of imperfect work being 25 produced is thus avoided. After the feed has taken place the presser-foot *e* is again brought down onto the work, and as the needle continues to rise an adjustable block or projection, 12, on the cast-off bar *d* is brought into contact with an adjustable projection, 13, Fig. 1, 30 on the inner side of the bar *H*, which is thus raised during the latter part of the ascent of the needle-bar, and simultaneously with this upward movement the frame *G* is oscillated 35 back to its original position, which allows the bar *H* to spring out and follow the inclined face 16 of the piece *q*, which brings it back to the position from which it started, ready to again descend onto the welt and push it outward as before.

By causing the projection on the rod *K* to strike against a stiff spring, *p*, instead of against a rigid projection on the bar *H*, the latter is enabled to accommodate itself to soles of varying thicknesses.

By adjusting the supporting bar *L* toward or from the tip of the horn the distance of the row of stitches from the edge of the welt may be varied as desired, and as the distance to 55 which the edge of the welt projects beyond the upper depends upon the distance between the central portion, 18, of the roll and the outer

edge of the lower flange, *w*, different guide-rolls are used for different kinds of work, in which case the bar *L* is adjusted to bring each 60 roll into the exact position required with respect to the tip of the horn. The bar *H* and guide-roll *M* thus form a simple automatic device, by means of which the welt is held while being sewed in the exact position required without any especial attention on the part of the operator.

What I claim as my invention, and desire to secure by Letters Patent, is—

1. In a boot and shoe sewing machine, the 70 combination, with a gage or rest for the edge of the welt and the upper of the boot or shoe, of a sliding bar, *H*, adapted to be brought down upon the welt, and having a longitudinal and lateral movement, substantially as described, for pushing or pressing the welt outward against the gage or rest and keeping it 75 constantly in contact therewith, as and for the purpose set forth.

2. In a boot and shoe sewing machine, the 80 combination, with the work - supporting horn *D* and stitch-forming devices, of the longitudinally and laterally moving push - bar *H*, and the flanged guide-roll *M*, adapted to form separate gages for the outer edge of the welt and 85 the contiguous edge of the upper or vamp, whereby the welt is maintained at a uniform or unvarying distance from the vamp throughout its entire length, substantially as and for the purpose described.

3. The sliding push-bar *H*, with its spring *p*, adapted to be moved downward in guides on the oscillating frame *G* by the contact with the spring of a projection, *m*, and upward by the contact of a projection, 12, with a projection, 90 13, thereon, in combination with the piece *q*, having an inclined face, 16, whereby the lower end of the bar *H* is caused to move obliquely to push the welt outward from the sole and keep it constantly in contact with the inner portion, 18, of the gage-roll *M*, substantially as and for the purpose set forth.

4. The combination, with the horn *D* and the sliding push - bar *H*, of the guide - roll *M*, with its central portion, 18, and upper and lower flanges, *v w*, mounted upon a supporting arm, *L*, made adjustable on the frame-work, substantially as and for the purpose described.

Witness my hand this 23d day of June, A. D. 1881.

WILLARD COMEY.

In presence of—

P. E. TESCHEMACHER,
CHAS. E. GRIFFIN.
